UNITED STATES PATENT OFFICE.

JOSEPH P. MCKEE, OF ALLEGHENY, PENNSYLVANIA.

TELEPHONE-NOTATION REGISTER.

SPECIFICATION forming part of Letters Patent No. 731,805, dated June 23, 1903.

Application filed April 21, 1902, Serial No. 104,030. (No model.)

To all whom it may concern:

Be it known that I, JOSEPH P. MCKEE, a citizen of the United States of America, residing at Allegheny, in the county of Allegheny and State of Pennsylvania, have invented certain new and useful Improvements in Telephone-Notation Registers; and I do hereby declare the following to be a full, clear, and exact description thereof, reference being had to the accompanying drawings, which form a part of this specification.

My invention relates to certain new and useful improvements in telephone - notation records.

15 The device is adapted to be attached to or made a permanent part of the telephone-transmitter, where the same may be easily and quickly referred to.

In the accompanying drawings, forming a part of this specification, Figure 1 represents a metallic case, circular in form, to receive the record, the obverse side being shown in the view with the reverse side of the cover or lid in dotted lines. Fig. 2 is a side view of a 25 telephone-transmitter with my notation device attached. Fig. 3 is an inside view of the rear part of the case. Fig. 4 is a plan view of the notation-record. Fig. 5 is a side view of a modified notation device attached to a telephone-transmitter. Fig. 6 is an inner view of the modified notation device, showing a 30 single closed plate or record covering.

Referring to the several views in the accompanying drawings, the numeral 1 designates 35 the front portion of the record-holding case.

2 is the mouthpiece of the telephone-transmitter.

3 is an opening in the disk 1.

4 is a cut-out in the periphery of the case to 40 rotate the record within by the finger.

5 is the rear or under portion of the case.

6 are spring-catches stamped out of the portion 5.

7 is the telephone-transmitter.

8 are radial sections on the record-disk.

9 is the milled or saw edge formed on the periphery of the record-disk to facilitate revolving the same when placed in position within the case.

10 are set-screws for fastening my modified device to the transmitter.

11 is a flange formed on my celluloid notation-record for use in fastening on the transmitter.

12 is the circular opening in the case and 55 record - disk for receiving the telephone-mouthpiece.

13 is a fastening device made integral with or soldered to the case.

14 is the hinge connecting the two parts of 60 the case. (Shown in Figs. 1 and 3.)

The notation-record, as shown in Fig. 4, is placed within the circular case. (Seen in Fig. 1.) This case is then affixed to the telephone-transmitter and secured thereto by the springs 65 66 or set-screws 10. Instead of using the case seen in Fig. 1 I can substitute the circular case seen in Fig. 6 to inclose the register, Fig. 4, this modified case being attached to the telephone - transmitter and secured thereto by 70 means of the set-screws 10 and part 13. When thus placed in position by either of the above-described methods and the operator desires to call up a particular person he turns the 75 name desired appears at the opening 3 of the disk. This opening will show but one name at a time.

Having thus shown and described my invention, what I claim as new, and desire to 80 secure by Letters Patent of the United States, is—

In a telephone-notiation device, the combination with a telephone-transmitter, the case having spring-fastenings to engage the transmitter for securing said case, a hinged cover on said case having a sight-opening and a record-disk arranged in said case and having indications which show through said sight-opening.

In testimony whereof I have hereunto affixed my signature in the presence of two subscribing witnesses.

JOSEPH P. MCKEE.
